UNITED STATES PATENT OFFICE.

EDWARD W. MITCHELL, OF OBERLIN, OHIO.

MARINE PROPULSION.

SPECIFICATION forming part of Letters Patent No. 611,182, dated September 20, 1898.

Application filed March 16, 1897. Serial No. 627,804. (No model.)

To all whom it may concern:

Be it known that I, EDWARD WELLINGTON MITCHELL, of Oberlin, in the county of Lorain and State of Ohio, have invented a new and useful Improvement in Marine Propulsion, of which the following is a specification.

My invention is an improvement in marine propulsion, providing a simple novel construction of reciprocating propeller and devices for operating the same; and the invention consists in certain novel constructions and combinations of parts, as will be herein-after described, and pointed out in the claims.

In the drawings, Figure 1 is a top plan view, and Fig. 2 a bottom plan view, of a boat provided with my improvements. Fig. 3 is a detail vertical longitudinal section of a part of the boat, and Fig. 4 is a detail perspective view of the propeller.

By my invention I provide one or more reciprocating propellers A, which slide back and forth along the hull of the boat, and in connection with the blades of such propellers supply means whereby they may be reversed to act operatively in a reverse direction, so the propeller may be utilized in stopping the boat and in moving it stern foremost. On the hull I provide tracks or ways C for the propeller or propellers A, which may be duplicated, as shown, so the description of one of such propellers—say the middle one—and of the devices for operating the same will suffice for the description of all. In the construction shown I supply a middle propeller and two side propellers, the area of the latter two equaling that of the middle one, and they operating reciprocally with the middle propeller, so the movements of the boat will be smooth and easy and all sudden jars and shocks will be avoided.

I will now proceed to describe one of the propellers A, which may be said to have a carriage D, sliding in the ways C, the blade E, pivoted to the carriage D, braces or guys F F' for the sliding plate, and a support G for such guys F F', which support slides with respect to the pivot of the blade, together with means whereby the said support may be moved in one direction or the other, such means preferably consisting, as shown, of a journaled drum H, having a pinion h meshing a rack g on the support G, so the turning

of drum H in one direction or the other will correspondingly move the support G. The guys F F', connecting the blade with the support G, are alternately slackened or tightened by the movement of the support G in one direction or the other. Thus if the support G be moved forward toward the bow of the boat the guys F will be slack and the guys F' taut, so the propeller-blade will act operatively when moved forward and folded when moved sternward, so the propeller would serve to back the boat. If, on the other hand, the support G be moved sternward, the guys F' will be slack and the guys F taut, so the blade will propel the boat forward as such blade moves sternward and will fold as it moves toward the bow.

To operate the drum in a simple manner, I connect therewith the ends I I' of the cable, which reciprocates the propeller, said ends I I' leading the former forward and the latter back and passing over pulleys i i' to the operating mechanism. The cable ends I I' are wound on the drum in opposite directions, so one can only turn the drum by winding on the same the other end of the cable to the same extent to which the first end is wound off in turning the drum, and in effecting such result I provide a cable-adjusting mechanism, which will be presently described in detail, which takes up the cable in such manner as to slacken one end and draw up the other end to turn the drum in one direction or the other to effect the adjustment of the support, as described. This cable-adjusting mechanism may be an ordinary capstan J, around which the cable is wound, such capstan being arranged to be turned in the usual manner and having a common detent j, by which it may be held in any position to which it may be turned. This capstan serves to enable the ready reversal of the propeller by setting the blade to act operatively on the forward or backward movement of the same.

To operate the propeller back and forth, I provide a reciprocating operating device connected with the cable and serving to draw the same back and forth to reciprocate the propeller. This reciprocating operating device may be a piston K, operating in a cylinder L and driven by steam or other power and connected with the cable in such manner as

to operate it as desired. In the construction shown and as preferred I provide the reciprocating operating device K with a series of guide-pulleys *k*, and also provide pulley-blocks M and M', around whose pulleys the cable leads to the propeller, so the movement of the operating device back and forth may be multiplied or increased in its transmission to the propeller, thus securing a considerable movement of the propeller with but a limited movement of the operating device. Manifestly, as before suggested, the number of the propellers may be increased, and, where desired, they may be arranged along the sides 15 as well as upon the bottom of the boat.

Having thus described my invention, what I claim as new, and desire to secure by Letters Patent, is—

1. A propeller comprising a carriage, a blade pivoted thereto, guys secured to and leading in opposite directions from said blade, a movable support to which said guys are connected and devices by which to adjust said movable support substantially as described. 20
25 2. A propeller comprising a carriage, a pivoted blade, a support sliding with respect to the pivot of the blade, the braces or guys connecting the blade with the support on opposite sides of the pivot of the blade and means by which to slide said blade substantially as described.

3. A propeller comprising a pivoted blade, guys or braces leading in opposite directions from the blade, a support to which said braces or guys are connected, such support being movable with respect to the pivot of the blade, a drum geared with the said support and means by which to turn said drum to adjust the support substantially as shown and described. 35
40

4. In a propeller the combination with the blade, and the movable support by which to reverse said blade, such support having a rack, of the drum having a pinion meshing 45 with the rack the cables on said drum and means for operating said cables substantially as shown and described.

5. A propeller substantially as described consisting of the carriage, the blade pivoted 50 to the carriage, the support sliding in said carriage and extending on opposite sides of the blade and provided with a rack, the braces or guys connecting the support with the blade, the drum journaled to the carriage and having a pinion meshing with the rack of the support and the cable by which to turn the drum substantially as described. 55

6. In a propeller the combination with the carriage the blade, and devices by which the 60 blade may be braced to act operatively in one

or the other direction of the cable for operating said propeller, the ends of such cable being connected with the bracing devices of the blade whereby the same cable may serve to adjust the blade and also operatively move 65 the propeller substantially as shown and described.

7. The combination of the pivoted blade, the carriage therefor, means by which to adjust the said blade to act operatively in one or the other direction such means including a drum, the cable wound at its ends on said drum and an adjusting means whereby one of such ends may be wound on and the other correspondingly wound off the drum to effect the desired 70 adjustment of the blade substantially as described.

8. The combination of the sliding carriage, the pivoted blade, the braces or guys therefor, the supports to which the braces or guys 80 are connected, the drum geared with said support, the cable wound at its ends on said drum and the capstan on which said cable is wound, and operating devices connected with said cable for moving the propeller, substantially as described. 85

9. The apparatus herein described consisting of the reciprocating propeller, the reciprocating operating device, the cable connecting said propeller and operating device, a plurality of pulleys being provided on the reciprocating device and pulley-blocks having a plurality of guide-pulleys and arranged between the operating device and the propeller substantially as shown and described. 90
95

10. In an apparatus substantially as described the combination of the reciprocating propeller, the reciprocating operating device, having at its ends the plurality of pulleys the pulley-blocks adjacent to said ends and having pulleys, the adjusting device, and the cable secured at its ends to the propeller, passed about the adjusting device and disposed through the pulleys of the blocks and operating device substantially as shown and described. 100
105

11. The apparatus herein described consisting of the reciprocating propeller, the reciprocating operating device having pulleys, the pulley-blocks adjacent to the ends of the reciprocating device, the capstan for adjusting the cable, and the cable secured at its ends to the propeller passed through the pulley-blocks and pulleys of the operating device and about the capstan substantially as described. 110
